UNITED STATES PATENT OFFICE.

GEORGE S. GATCHELL, OF ROSELLE PARK, NEW JERSEY, ASSIGNOR TO THE SINGER MANUFACTURING COMPANY, A CORPORATION OF NEW JERSEY.

TAKE UP.

1,414,352.

Specification of Letters Patent.

Patented May 2, 1922.

Application filed May 23, 1919. Serial No. 299,328.

To all whom it may concern:

Be it known that I, GEORGE S. GATCHELL, a citizen of the United States, residing at Roselle Park, in the county of Union and 5 State of New Jersey, have invented certain new and useful Improvements in Take Ups, of which the following is a specification, reference being had therein to the accompanying drawings.

10 This invention relates to a needle-thread take-up for sewing machines, more particularly to a take-up for plural-needle-chain-stitch machines having a single looper.

It is desirable in machines of this type, as 15 the looper is retracted and successively sheds the previously formed needle-loops encircling it, that each of these loops be rapidly drawn up in the order shed instead of simultaneously when the last one has been shed, 20 as this allows a sufficient supply of looper-thread to be drawn in as each needle-loop is tightened and avoids placing an extra strain on the looper-thread.

The object of the present invention is to 25 provide a take-up for accomplishing the above stated result, which will be simple in construction and economical in manufacture.

In the drawings, Fig. 1 is a front end view 30 of a machine, with parts broken away showing the position of the take-up as the looper is about to shed its first loop. Fig. 2 is a top plan view of the take-up. Fig. 3 is a view 35 of the take-up from the side opposite to Fig. 1, with the cast-off arms about to shift the thread from a horizontal portion of a take-up slot to an inclined portion. Fig. 4 is an elevation showing the take-up elements in end view with the take-up at its highest point. Fig. 5 is a view of the take-up plate 40 detached and showing it as arranged for three threads. Fig. 6 is a detail sectional view showing the position of one of the threads in the take-up when the looper is shedding the loop of said thread as shown 45 in Fig. 1. Fig. 7 is a detail sectional view showing the position of the second thread in the take-up as its thread-loop is being shed by the looper.

Referring to the drawings, 1 represents 50 the head of a sewing machine bracket-arm, 2 the needle-bar, 3 the needles, 4 the presser-bar and 5 the presser-foot. A work-arm 6 is located below the head and in said work-arm is a looper 7 cooperating with the needles.

3. Any suitable means may be provided for 55 actuating the stitch-forming mechanism. Secured to the upper end of the needle-bar is a take-up plate 8. This plate is provided with thread-apertures, in the present instance two in number. The aperture 9 for 60 the thread *b* whose needle-loop is first engaged by the looper is in the form of a circular eyelet. Disposed alongside of said eyelet is an aperture 10 for the second thread *a*, which aperture is in the form of an angle-shaped slot having an inclined portion 10^a 65 extending above and below the eyelet 9, and a horizontal portion 10^b at its lower end forming an acute angle with the inclined portion and defining a horizontal shoulder 70 10^c. A horizontal plate or arm 11 has a downwardly turned shank 12 adjustably secured to the side of the machine head by the set-screw 13 entering slot 14. At its free end the arm 11 is forked to provide arms 15 75 extending on each side of the path of the take-up plate adjacent the eyelet 9, the extremities of the arms 15 being upturned at 16 to retain the thread. A horizontally disposed shank 17 (Fig. 3) is adjustably secured 80 to the top of the machine head by a set-screw 19 entering a slot 18 and said shank carries a pair of cast-off arms 20 disposed on opposite sides of the path of the take-up plate adjacent the aperture 10. Said arms have inclined edges 21 which act at the proper time 85 to cast off the thread from the shoulder 10^c in the horizontal slot portion 10^b to the inclined portion 10^a.

Disposed in front of the take-up is a 90 slack-thread controller comprising a vertical standard 22 adjustably secured to the machine head by a set-screw 23 entering a slot 24. The standard is forked or slotted transversely of the path of the needle-threads to form arms 25 and 26. The back portions of said arms are extended upwardly at 27, 28, to form guides for a spring-wire slack-thread controller 29, the free end of which is movable up and down in the space 95 between the arms 25 and 26 and their extensions 27 and 28. The other end of the wire is coiled around a screw 30 secured to an arm 31 adjustably mounted on the machine head by a set-screw 32 entering a slot 33. 100 The tension of the spring-arm may be varied by securing the coiled end of the controller 29 in either of the holes 34 in the 105

arm 31. The extent of downward movement of the free end of the controller 29 is limited by an adjustable stop comprising a slotted plate 35 secured to the extension 5 28 by a screw 36 and having an arm 37 at its lower end projecting across the space between arms 25 and 26 in the path of the controller. The arm 26 is slotted at 38 and 10 39 to form thread-guiding openings or apertures and the upper portion of the slotted part is turned over forwardly and horizontally as shown at 40. The threads pass over the upper edge of the rear arm 25 between the extension 27 and an extension 41, which 15 latter is bent forwardly at its upper end at 42 and overhangs the part 40.

A standard 43 projects upwardly from the machine head, and pivoted at its upper end is a rock-lever 44, one end of which carries 20 pull-off and slack-thread controlling arms 45 and 46, while the other end of the lever is connected by a link 47 to the presser-bar in a manner well known and forming no part of the invention. The slack-thread controlling arms act in the ordinary manner to vary the amount of thread pulled off by the take-up, the presser-foot rising and falling in accordance with the thickness of the material and correspondingly lowering or raising the 30 thread-controlling arms.

If more than two needles are used additional angle-shaped slots 10' are provided in the take-up plate as shown in Fig. 5, the horizontal portions of said slots being disposed at successively lower elevations. It is obvious that the inclined portions of the slots may be turned in the reverse direction if desired, and all the threads may be controlled by the angle-shaped slots, if desired, 40 instead of using the eyelet 9 for the last one.

In operation, when the needles are all the way up the needle-bar and take-up are in the position shown in Fig. 4, with the thread *a* in the horizontal slot portion 10^b, the looper is in extreme forward position and encircled by the two previous needle-loops, and the spring wire slack-thread controller is pulled up. As the needles and take-up start down, the looper starts rearwardly and the spring wire 29 takes up the slack in the needle-thread. The needles enter the well known triangles formed by the looper, its thread and the previous needle-loops. Before the needles reach their lowest position, the previous needle-loop of thread *a* is shed by the looper, but just previous to its shedding the shoulder 10^c formed by the upper wall of the horizontal slot portion 10^b of the take-up passes below the plane of the thread *a* leading to the tension at the rear of the overhanging arm and has placed said thread under additional tension (see Fig. 6). Hence as the loop of thread *a* is shed it is at once drawn up into the work and out of the way. 65 On further retraction of the looper the pre-

vious needle-loop of thread *b* is shed and at this time the eyelet 9 of the take-up passes below the plane of the thread-guiding arms 15 at each side of it, placing the thread *b* under tension and quickly drawing up the 70 loop thus shed (see Fig. 7). Shortly after the loop of thread *b* is drawn up the take-up plate has moved down to the position shown in Fig. 3 and the inclined edges 21 of arms 20 cast off the thread *a* from the 75 shoulder 10^c. When the looper reaches its extreme rearward position the needles are all the way down and the doubling of the threads along the needles has drawn up the 80 spring wire thread-controller 29. As the looper goes forward and the needles rise the controller 29 descends and takes up the slack, but it reaches its bottom position 85 quickly and allows enough slack thread to form to produce the needle-loops for entry by the looper. As the take-up plate rises with the needle-bar the thread *a* slips down the inclined slot portion 10^a and into the horizontal portion 10^b again, the take-up continues to rise and successively tightens 90 the needle-threads around the advancing looper, and the take-up parts again assume the position shown in Fig. 4.

Having thus set forth the nature of the invention, what I claim herein is—

1. In a sewing machine, a movable take-up member having an extended thread-aperture therein, thread-guides cooperating with said take-up member and cast-off means coacting with said aperture to cast off the 100 thread from one part of the aperture to another as the take-up action is completed.

2. In a sewing machine, stitch-forming mechanism including a needle and a looper, a needle-thread take-up having a thread-aperture with inclined portions, one of which has a wall adapted to instantly take up a needle-loop as it is shed from the looper, and means coacting with said wall to shift the needle-thread to the other portion of the 110 aperture after the loop has been taken up.

3. In a sewing machine, stitch-forming mechanism including a needle and a looper, a needle-thread take-up movable across the path of the thread and having a thread-slot 115 with differently directed portions, one of which has a wall at substantially right angles to the path of the thread and inclined to shift the latter into the second portion, and a second portion having a wall transverse to the path of the thread to take up the same, and means for shifting the thread from the second portion to the first as the take-up action is completed.

4. In a sewing machine, stitch-forming 125 mechanism including a needle and a looper, and take-up means for the needle-thread comprising a relatively movable thread-guide and take-up member, said take-up member having a thread-aperture, a portion 130

of whose wall acts as a take-up, and cast-off means for shifting the thread away from said wall as the take-up action is completed.

5. In a sewing machine, stitch-forming mechanism including a needle and a looper, a needle-thread take-up comprising a movable member having an angle-shaped thread aperture therein to quickly draw up the needle-loop as it is shed from the looper, and 10 stationary members coacting with said aperture to cast off the thread from one portion of said aperture to another after it is drawn up.

6. In a sewing machine, a movable take-up member having an extended thread-aperture therein formed with a thread-detaining portion, thread-guides cooperating with said thread-detaining portion and a cast-off coacting with said aperture to cast off the 20 thread from the detaining portion of the aperture to another portion as the take-up action is completed.

7. In a sewing machine, a head, multi-needle single-looper stitch-forming mechanism including a plurality of needles, a needle-bar and a single looper, and coacting take-up devices carried by the needle-bar and head and including means having a plurality of differently shaped apertures for successively taking up the needle-thread loops immediately as they are shed by the looper.

8. The combination with stitch-forming mechanism including a reciprocating needle-bar carrying a needle, of needle-thread take-up means including a thread-engaging device mounted on the needle-bar and having a shoulder adapted to engage and take up the needle-thread, and a cast-off for dislodging the thread from said shoulder before the needle-bar completes its stroke.

9. In a sewing machine, in combination, a reciprocating needle-bar carrying a needle, a looper cooperating with said needle to form stitches, a thread-engaging device 45 mounted on the needle-bar and formed with a shoulder adapted to engage the needle-thread and quickly take up the needle-thread loop shed by the looper, and a cast-off for dislodging the needle-thread from said shoulder after the needle-loop is tightened and before the needle reaches the end of its down stroke.

10. In a sewing machine, stitch-forming mechanism including a plurality of needles 55 and a single looper cooperating therewith to form stitches, take-up means movable across the path of the needle-threads and having a plurality of thread apertures therein defin-

ing shoulders at different elevations adapted to successively take up the needle-loops as 60 they are shed by the looper, and means for successively shifting the respective threads from one of said portions to another as their take-up action is completed.

11. In a sewing machine, stitch-forming mechanism including a plurality of needles and a single looper cooperating therewith to form stitches, a member having thread guiding openings arranged in a plane, take-up means movable across the path of the threads 70 and having a plurality of thread-apertures therein, each aperture having angularly related take-up and idle portions, the take-up portions being disposed successively at different distances from the plane of the thread 75 guiding openings, and means for shifting the threads to the idle portions of the apertures as their take-up action is completed.

12. In a sewing machine, stitch-forming mechanism including a needle-bar, a plurality of needles and a looper, a stationary thread-guide having thread apertures therein, a cooperating take-up member carried by the needle-bar and provided with thread-apertures, each of said latter apertures having a horizontal take-up portion and an inclined idle portion leading therefrom, and stationary cast-off means for shifting the threads from the take-up portion to the idle portion after the threads are drawn up. 90

13. In a sewing machine, stitch-forming mechanism including a plurality of needles and a looper, and means for successively taking up the needle-threads as they are shed by the looper, said means comprising relatively movable elements, each of which has a series of thread-guiding apertures therein, each aperture of one of said series having portions disposed at an angle to each other, and cast-off means for shifting the threads 100 from one of said portions to the other. 95

14. A sewing machine having, in combination, stitch-forming mechanism including a needle-bar carrying a plurality of needles, a single looper cooperating with said needles to form stitches, multiple thread take-up means mounted on the needle-bar and including a take-up shoulder for the thread of the first needle-thread loop shed by the looper on its retracting stroke, and a cast-off for dislodging the needle-thread from said shoulder after said needle-thread loop is tightened. 110

In testimony whereof, I have signed my name to this specification.

GEORGE S. GATCHELL.
